UNITED STATES PATENT OFFICE.

HERMAN JAKOBSSON, OF PHILADELPHIA, PENNSYLVANIA.

CONTROL MECHANISM FOR FIRING GUNS.

1,293,104.

Specification of Letters Patent.

Patented Feb. 4, 1919.

Application filed February 28, 1917. Serial No. 151,408.

To all whom it may concern:

Be it known that I, HERMAN JAKOBSSON, a citizen of the United States, residing at Philadelphia, county of Philadelphia, and State of Pennsylvania, have invented a new and useful Improvement in Control Mechanism for Firing Guns, of which the following is a full, clear, and exact description, reference being had to the accompanying drawings, which form a part of this specification.

In the manipulation of guns it is customary to provide for the operator a shoulder brace adapted to rest against the shoulder piece 15 which the operator grasps with one hand while with the other hand he manipulates the firing handle for actuating the trigger controlling the firing mechanism. It is obviously difficult to provide a shoulder piece 20 or handle of such character that it will be conveniently positioned at any elevation of the gun varying from below horizontal to nearly vertical. The object of my invention is to provide a shoulder piece which is adjustable, 25 or has an adjustable part, whereby the relation of the shoulder piece to the gun may be varied with the gun's elevation and whereby the handle on the shoulder piece may be at substantially the same position 30 relatively to the operator's seat regardless of the elevation of the gun.

A preferred embodiment of the invention is shown in the accompanying drawings, in which,—

35 Figure 1 is an elevation of a gun and carriage with parts broken away.

Fig. 2 is an enlarged fragmentary view of the connection between the shoulder piece and the arms forming guides for the firing 40 handle.

Fig. 3 is a section on the line 3—3 of Fig. 2.

45 *a* is one of the wheels of the gun carriage. *b* is the trail carrying a seat (not shown) for the operator. *c* is one of the trunnions about which the gun *d* is swung to adjust its angle of elevation in a yoke *g* which is mounted with its vertical pivot in a socket *h*, rigidly secured on the trail *b*. Both elevating and 50 traversing of the gun is accomplished by the gunner through the shifting of the shoulder up and down or sidewise, while pressing it against the shoulder piece.

55 If the gun is of a heavy type, it may be secured during the firing by clamps *j*, or any other suitable well known means. *e*

is the recoil cylinder. *f* is the breech block carrying the firing mechanism, the details of which are not shown, which is actuated by means of the firing handle 100, the latter 60 being slidably mounted on the two arms 101 secured to a non-recoiling portion of the carriage. The rear ends of the arms terminate in a plate 102 of T shape in cross-section, the curved rear arms 103 of the T fitting 65 engaging within a curved tubular member 104 forming the shoulder piece. The shoulder piece, provided with a longitudinal slot 109, is adjustable in the direction of its length along the plate 102 and is held in its adjusted 70 position by means of clamping plates 105 on opposite sides of the main arm of the plate 102, the plates 105 having flanges 106 fitting against the outside of the tube 104. The plates are held in position by 75 means of a clamping bolt 107 extending through them and the main arm of plate 102, which is for that purpose threaded in one of the clamping plates 105. To tighten the clamping bolt 107 its head is provided 80 with either a fixed or detachable handle 110. Secured to the ends of the shoulder piece 104 are handles 108, one or the other of which, dependent upon the angle of elevation of the gun, is firmly grasped by the 85 operator with one hand, while with the other hand he manipulates the sliding firing handle 100. The handles 108 also form abutments limiting the sliding movement of the shoulder piece upon plate 102. The shoulder 90 piece 104, together with the coating plates 103 and 106, are curved in the arc of a circle whose center is approximately the axis upon which the gun swings.

When the gun is depressed to about a substantially horizontal position or, as shown in the broken lines *x*, slightly below a horizontal position, the shoulder piece is adjusted to its lowermost position on its supporting arms, the operator grasping the 100 lower handle 108. When the gun is elevated to approximately the position shown in the broken lines *y*, the shoulder piece is adjusted to its uppermost position, as shown by the broken lines *z*, and the operator grasps the 105 upper handle 108. It will be evident that when the gun is elevated to this extreme angle or angles approaching the same, the gunner will be unable to press his shoulder against the shoulder piece 104, but that 110 the shoulder piece and the upper handle at that time together serve as a lever to move

the gun into the desired position and that the clamping handle *j* then comes into play for retaining the gun in elevation. The positions *x* and *y* represent the extreme limits 5 of depression and elevation. It will be understood that the shoulder piece may be adjusted to any intermediate position that will be best adapted to the angle of elevation of the gun.

10 In order to soften the blow against the man's shoulder upon firing the gun, a cushioning device is provided on the shoulder rest. This may preferably be made of rubber or other elastic material 112, which is 15 cured in any suitable manner on the outer surface of the tube 104 forming the shoulder rest. It has been found most practical to use a piece of hose or rubber tire, slit open along its entire length and cemented or 20 riveted to the tube 104.

Having now fully described my invention, what I desire to claim and protect by Letters Patent is:

1. In a gun mounting, the combination 25 with a gun and trunnions on which the gun is turnable to vary its elevation, of a rearwardly extending support secured to a non-recoil part of the gun, a shoulder piece slidably adjustable arcuately on said support, 30 means to maintain said shoulder piece in a plurality of positions corresponding to the various positions of elevation of the gun, and handles at opposite ends of the shoulder piece, whereby at widely varying gun 35 elevations, a handle for the operator may be provided at an approximately unvarying position.

2. In a gun mounting, the combination 40 with a gun and trunnions on which the gun is turnable to vary its elevation, of a rod

extending back from a non-recoil part of the gun, a firing handle slidable along the rod, a T-plate secured to the rear of said rod, a tubular shoulder piece slotted to receive the main arm of the T-plate and adapted to accommodate the outer arms thereof, clamping plates engaging opposite sides of the main arm of the T-plate and the adjacent outer wall of the tube, and means to clamp the clamping plates in position. 50

3. In gun mountings having a non-recoiling member provided with trunnions for elevating the gun; a shoulder piece, comprising a rearwardly extending arm rigidly secured on the said member, a guide at the extreme 55 end of said arm and a shoulder rest slidably mounted around the said guide in such a manner that the shoulder rest may be held either depending from said arm or standing upright thereon, and clamping means for 60 rigidly securing the shoulder rest in any one of the said positions.

4. In gun mountings having a non-recoiling member provided with trunnions for elevating the gun, a shoulder rest comprising a rearwardly extending arm rigidly secured on the said member, an arcuate guide at the extreme end of said arm and a shoulder rest movably mounted on the said guide in such a manner that the shoulder rest may 70 be held either depending from said arm or standing upright thereon and clamping means for rigidly securing the said shoulder rest in any intermediary position between the said extreme positions. 75

In testimony of which invention, I have hereunto set my hand, at Philadelphia, on this 12th day of February, 1917.

HERMAN JAKOBSSON.
